(57) **CLAIM**

The ornamental design for an electronic device, as shown and described.

DESCRIPTION

FIG. 1 is a perspective top view showing our new electronic device design;

FIG. 2 is a top view thereof;

FIG. 3 is a side view thereof;

FIG. 4 is another side view thereof;

FIG. 5 is a front view thereof;

FIG. 6 is a back view thereof;

FIG. 7 is a perspective bottom view thereof;

FIG. 8 is a bottom view thereof; and,

FIG. 9 is an enlarged perspective view of a bottom portion thereof.

In the drawings, the broken lines depict environmental subject matter only and form no part of the claimed design.
